UNITED STATES PATENT OFFICE.

ALEXANDER C. HUMPHREYS, OF PHILADELPHIA, PENNSYLVANIA, ASSIGNOR
TO THE WELSBACH INCANDESCENT GAS LIGHT COMPANY, OF NEW JERSEY.

GAS-BURNER FOR INCANDESCENT ILLUMINATION.

SPECIFICATION forming part of Letters Patent No. 416,624, dated December 3, 1889.

Application filed December 15, 1887. Serial No. 257,993. (No model.)

To all whom it may concern:

Be it known that I, ALEXANDER C. HUMPHREYS, a citizen of the United States, residing at Philadelphia, (Chestnut Hill,) in the county 5 of Philadelphia and State of Pennsylvania, have invented new and useful Improvements in Gas-Burners for Incandescent Illumination, of which the following is a specification.

My invention has for its object to provide 10 an improved gas-burner for consuming non-carbured water-gas or water-gas in producing light by the incandescence of a refractory hood or mantle suspended over the burner, as in the Welsbach system of incandescing 15 gas-lighting.

The invention is illustrated in the annexed drawings, in which—

Figure 1 represents my improved gas-burner in partly-sectional side elevation with 20 a gallery attached for supporting a mantle or hood above the burner, and a chimney in which said hood is inclosed. Fig. 2 is a perspective view of my improved water-gas burner; and Fig. 3 is a longitudinal section 25 of the same.

The burner consists of a tube or hollow cylinder 1, having a nearly-uniform diameter throughout its length. The upper end of this tube is closed by a flat plate 2, which is preferably supported in and slightly below the upper end of the tube, as shown in Fig. 3, while the lower end of the tube is open and slightly flared for attachment of a thimble 3, which is shrunk or swaged thereon. In the 35 plate 2, which closes the upper end of the tube 1, is formed an annular series of perforations 4, located near the outer edge of the burner, as shown in Fig. 2, to cause the gas to issue in an annular series of jets in close 40 proximity to the tubular hood or mantle which is to be suspended over and around the upper end of the burner.

The thimble 3 on the lower end of the burner is internally threaded to engage a gas-fixture 5, as shown in Fig. 1, and on the tube 1, above the thimble, is spun an annular shoulder 6, which may serve to support a lamp-gallery 7, placed around the burner. This gallery may be formed, as usual, to support 45 a chimney 8 and a globe 9, or it may be of such diameter as to be capable of support-

ing a chimney only. To the under side of the gallery-body are attached arms 10, connecting with a ring 11, that can be made to support the gallery by resting on the annular shoulder or head 6; or the gallery may be supported or suspended from its upper end by means of an inwardly-flanged ring or collar 12, resting on the top of the burner-tube. This ring or collar is connected with the gallery-body by ribs 13, that are braced by a horizontal ring 14, integral therewith, and thereby imparting to the gallery a proper degree of rigidity. This horizontal ring is located slightly above a point midway the 65 length of the several ribs 13, and so offers an obstruction to the passage of a match into forcible contact with the mantle or hood in igniting the gas.

The upper end of the mantle or hood 15 is 70 attached by a platinum wire 16 to a horizontal ring 17 on the upper end of a vertical rod 18, which is adjustably supported by means of a set-screw 19, in a perforated lug 20, formed on the gallery. 75

By igniting the water-gas issuing from the annular series of perforations or gas-exits 4 in the upper end of the burner a number of intensely-heating flame-jets will be brought in such proximity to the interior surface of 80 the tubular hood or mantle 15 as will quickly cause it to emit a brilliant light by incandescence, and thus enable the heating but non-illuminating qualities of water-gas to be utilized for illuminating purposes in the most 85 efficient manner.

What I claim as my invention is—

A gas-burner for incandescent illumination, consisting of a straight tube 1, provided with an internally-threaded attaching-thimble 3 at 90 its lower end, an annular bead 6, located on the tube above said thimble to afford support for a chimney-gallery, and a horizontal plate 2, set directly into and closing the upper end of the tube and provided with an annular 95 series of gas-exits 4, substantially as described.

In testimony whereof I affix my signature in presence of two witnesses.

ALEXANDER C. HUMPHREYS.
